CHARLES E. DREES AND ARNOLD E. DREES, OF ST. LOUIS, MISSOURI.

COMBINATION-LOCK KNOB.

Application filed December 16, 1925. Serial No. 75,671.

- Our invention relates to improvements in combination lock knobs, and more particularly, to a knob, for the operation of a lock bolt, having permutation controlled elements which render the knob capable or incapable of affecting movements of the lock bolt and which is rendered effective only upon a manipulation to a predetermined set up combination.
- 10 The object of our invention is to provide a knob for this purpose, of simple and inexpensive construction, which may be employed in substitution for the regular knob and by which the lock bolt may be moved 15 without the use of a key.

Drawings.

- Fig. 1 is an edge view partly in section of a door equipped with an ordinary lock to 20 which has been applied the combination knob of our invention.

Figs. 2, 3 and 4 show respectively front, side and rear views of our improved knob.

- Fig. 5 is an inside face view of the outer 25 knob element.

Fig. 6 is a sectional elevation taken on the line 6—6 of Fig. 5.

- Fig. 7 is a vertical sectional elevation of the inner knob element.

- 30 Fig. 8 is a rear face view of the inner knob element.

Fig. 9 is a forward face view of a tumbler race plate.

- Fig. 10 is a side view of the same race 35 plate.

Fig. 11 is a rear face view of the same race plate.

- Fig. 12 is an inverted plan view of the same race plate.

- 40 Figs. 13 and 14 are respectively face and edge views of a closure plug.

Fig. 15 is a front face view of a tumbler race plate complementary to the race plate shown in Fig. 11.

- 45 Fig. 16 is an edge view of the same plate.

Fig. 17 is a rear face view of the same plate.

- 50 Figs. 18, 19 and 20 are respectively front, side and rear views of a controlling sleeve.

- Figs. 21 and 22 show respectively rear and edge views of a fillet plate.

Figs. 23 and 24 show respectively edge and front views of a retaining socket.

- 55 Figs. 25 and 26 show respectively side and rear views of a torque bar.

Figs. 27 and 28 are respectively front and side views of the general assembly screw.

Fig. 29 is a view of a pair of button positioning springs.

Fig. 30 is a front elevation of a pair of 60 tumblers.

Figs. 31, 32 and 33 are part sectional views of tumbler, tumbler race, balls, manipulative button, ball receptacle, control sleeve and housing and show three positions of the 65 combination in the process of operation.

Description.

In the application of our device, assuming an ordinary door A, and lock B comprising 70 spring locking bolt 34 and rocker 35, the knob shank is removed and is replaced by two elements, one of which is the half-length knob shank 36, which extends into the rocker 35, and which is retained in position 75 by screw 37 residing between the door A and escutcheon plate 38, and the other of which is our combination lock knob C which is so arranged as to normally not engage with the rocker 35, but which may be made to engage rocker 35 and operate it provided a predetermined combination has been set up and knob C thereafter pressed into this engagement.

80 In applying knob C we remove the lock B from the door A, and escutcheon plates 38 and 39, and insert retaining socket 40. Torque bar 41 is inserted in retaining socket 40 through the knob opening 42 and lock B is then replaced whereby retaining socket 90 40 and torque bar 41 are maintained substantially in position. The socket 40 is so formed as to serve to lock the torque bar 41 against removal from its seat in the door A (see Fig. 1).

85 With lock B reinserted in the door, and with retaining socket 40 and torque bar 41 in position the door and lock are ready to receive the knob C and the regular knob D. To place the regular knob D, we insert the half shank 36 through escutcheon plate 38 and retain it by screw 37 and then apply escutcheon plate to the door which brings the shank 36 into engagement with rocker 35.

100 In applying knob C to the door fillet plate 43 is engaged by screws 44 and any other form of filling, such as 45, may be inserted for the mechanical support of escutcheon plate 39. Assembled knob C is now slipped over torque bar 41 and screw 46 is inserted through 105

110

assembled knob C to engagement with torque bar 41. Assuming the combination of knob C to be so arranged as to be operable, inner knob element 48 can slide on control sleeve 49, and in tightening screw 46 knob C is slid into proximal position to the door. In this position it will be found that the head of screw 46 approaches and cannot turn between lugs 50 of tumbler race plate 51, and further, 5 the thickness of the head of screw 46 and the corresponding depth of the space between the lugs 50 is such that the travel of knob C along control sleeve 49 provides for engagement or disengagement of torque bar 41 and 10 rocker 35.

When knob C is released after engaging screw 46 with torque bar 41 it is pushed forward by spring 52, its travel being limited by screw 46 bottoming in the housing provided between lugs 50 of tumbler race plate 51. The depth to which screw 46 is inserted in torque bar 41 is a function of the thickness of the door A, whereby adjustability to doors of differing thicknesses is provided. 20

It will be noted at this point, that it is necessary to have the combination in operable positions in order to place knob C and conversely this applies to its displacement, in consequence whereof, one unfamiliar with 25 the combination cannot remove knob C and thus operate lock B. When knob C is thus applied to the door by means of seating screw 46 in torque bar 41, closure element 53 is screwed into position to prevent screw 46 and 30 torque bar 41 from backing out and thus providing positive engagement of torque bar 41 with rocker 35.

Knob C which we have thus far assumed as being assembled, consists of a front element 54 provided with a recess 55, threaded screw holes 56 and ball receptacles 57. In assembling knob C tumbler race plate 51 is placed in element 54 so that the lugs 50 occupy recess 55, and companion tumbler race 40 plate 58 is placed on race plate 51, and these two plates are retained in position in front element 54 by screws 59 passing through holes 58' and 60 into threaded holes 56.

Before completing this assemblage tumblers 61 are inserted in tumbler raceways 62 and it will be noted that these tumblers, each of which has a segmental portion removed forming recesses 63, are different, in the location of these recesses, and the position of 50 these recesses is definitely related to the number of times button 64 must be operated to let its individual tumbler 61 assume an open position in the combination.

At the same time the tumblers 61 are inserted and before plate 58 is finally set by 60 screws 59, buttons 64 are inserted in holes 65.

With the combination thus far assembled, i. e., the forward portion containing two tumbler race plates which form the tumbler 65 races and with the tumblers housed against

removal in which lug 66 of front element 54 acts as one stop and button 64 as the other, the combination element of the lock is complete with the exception of the balls 67.

Balls 67, three in number for each tumbler, are now dropped into ball receptacles 57 through the openings 68 provided in the plate 51 which openings are in fact a continuation each of its tumbler race. 70

Plate 58 has on its rearward face a spring 75 housing 69 for the retention of springs 70, which springs engage with slots 71 of buttons 64 for the purpose of actuating the buttons and retaining them normally to the limit of their travels rearwardly. The 80 springs 70 are retained in the housing 69 by one of the screws 59.

With knob C thus far assembled and the balls placed, as has been stated, in the receptacles, they are free to travel into that part 85 of the raceways occupied by the tumblers provided the knob is inverted, by rotation, about the torque bar axis. If then the knob C is reinverted to its normal position, as shown in Fig. 1, the balls do not return to the receptacle 57 on account of a deflection 72 in their paths to the receptacles, but instead of that, they reside aligned in the axes 90 of the raceways, the lowermost ball in each raceway resting in the bay 73 of its button 64. 95

With the elements described assembled in front element 54 of knob C, control sleeve 49 carrying actuating spring 52 is set in position so that its prongs 74 are aligned to holes 75 of race plate 58 and clearance spaces 75' 100 of race plate 51, and inner knob element 48 is placed over control bolt 49 and slipped into outer knob element 54 where it is retained by screws 76 extended through holes 77 in element 48 and seated in threaded holes 105 78 in element 51.

Mode of operation.

Assuming the combination knob in position, as shown in Fig. 1, with all of the balls 110 in their raceways aligned beneath their respective tumblers and above their respective buttons, as shown in Fig. 31, the tumblers 61 are in such position that prongs 74 of control bolt 49 cannot travel into the 115 spaces 75' whereby torque bar 41 can engage with rocker 35 and thus operate lock B.

In order that prongs 74 may thus travel into spaces 75' it becomes necessary that tumblers 61, two of which limit the motion of each of the two prongs 74, shall be moved until the recess 63 of each tumbler shall afford clearance for prongs 74. This clearance is afforded by aligning recess 63 with hole 75 and clearance space 75' and is obtained by removing balls from under the tumbler, the number of balls to be removed depending upon the longitudinal location of the recess 63. 120

In order to remove the requisite number of 125

balls, button 64 is actuated, by the finger, to the position shown in Fig. 32, and then released. Upon its release, spring 70 returns button 64 to its initial position and drops ball 67 into receptacle 57. The dropping action being occasioned by the abutting, either of the following ball or the tumbler, this position is shown in Fig. 33. When the requisite number of balls has been removed from under the tumbler and when the companion tumbler under the given prong is similarly aligned and, further, when the two companion tumblers to the second prong 74 are similarly aligned, then control bolt 49 may travel relative to the remainder of knob C and knob C may be pressed in toward the door A and torque bar 41 may engage rocker 35 and lock B may be actuated, and if in any instance a greater number of balls be released from under any tumbler than the number necessary to align recess 63 into the trend of travel of prong 74, then the knob C may not be so actuated and the lock cannot be opened.

After the combination has been set and whether or not the lock has been actuated, the simple inversion of the knob C, by rotation to a position more or less opposed to that in which the combination operates, will permit all of the balls to return each into its respective raceway and between the tumbler and its button, and reestablish a position of all of the parts whereby upon the operation of the proper combination the lock may be again actuated.

As will be seen by reference to Figs. 31, 32 and 33 each full inward-and-outward stroke of the button 64 produces two positions of the column of spacing elements or balls 67, thus giving a wide range of combinations which may be effected.

Various modifications of structure may be

effected without departure from my invention as defined in the appended claims.

45

Claims.

We claim:

1. A combination lock knob embodying a permutation control assembly including a tumbler; a button; a series of spacing elements interposed between said tumbler and said button; said button being contoured to effect two adjustments of said column of spacing elements upon each full inward-and-outward stroke of said button. 55

2. In a lock of the class described, a knob, a torque bar movable with the knob into and out of effective positions relative to the bolt shifting means of a lock, a device for the control of movements of the torque bar, and 60 a permutation control for the said device comprising ball controlled tumblers.

3. In a combination lock knob a two-pronged control sleeve; a knob mounted on said control sleeve; a race plate fixedly 65 mounted within said knob; a plurality of buttons mounted through the rear face of said knob; and means operable by said buttons to bring the prongs of said control sleeve into operative engagement with said 70 race plate.

4. In a combination lock knob, a hollow knob; a race plate mounted in said knob and containing raceways; plungers mounted in each of said raceways; balls controlling the position of said plungers in said raceways; and transversely mounted buttons arranged to release said balls from said raceways and thereby alter the relative positions of said 75 plungers in their raceways. 80

In testimony whereof we hereunto affix our signatures.

CHARLES E. DREES.

ARNOLD E. DREES.
